UNITED STATES PATENT OFFICE.

ISAAC L. EDWARDS, OF AURORA, ILLINOIS.

SPIKE.

Application filed October 23, 1919. Serial No. 332,674.

To all whom it may concern:

Be it known that I, ISAAC L. EDWARDS, a citizen of the United States, and resident of Aurora, Illinois, have invented certain new and useful Improvements in Spikes, and do hereby declare that the following is a full, clear, and exact description thereof.

My invention relates to spikes for railroads and my object is to provide a spike, which in the most perfect embodiment of my invention, will require a minimum of material, for maximum strength and holding power, will not cut or unduly lacerate the fibers of the tie, will so interlock with the tie as not to be pulled out by the jars or vibrations of the rails and which when extracted will leave the tie in such condition that no plugging of holes will be necessary when the spike is again driven into the same.

20 In the drawings:—

Fig. 1, is a perspective view of a spike constructed to attain the object of my invention;

Fig. 2, is a horizontal section on line 2—2, 25 of Fig. 1.

My spike has a shank or body 10, which in cross section, is triangular and approximately T-shaped, with a head 11 of usual form and preferably a sharp, pointed entering end 12. One side of the shank (corresponding to the outer face of the head of the T), is flat, and that is the side which comes next the rail, and the stem 13 of the T has a series of horizontal corrugations 14 on its sides so that it extends vertically in a sinuous line, and the stem of the T is wedge-shaped in cross section, its sides diverging from its outer edge and merging with the head of the T. All edges of the shank are

rounded so as to avoid the formation of any sharp corners that would cut or lacerate the tie fibers.

It will be seen that when the spike is driven into the tie, the wedge form of the stem of the T crowds the spike against the rail, and the sinuous stem of the T readily penetrates the wood, but gently presses the fibers apart in opposite directions, and when driven home, the fibers press into the cavities of the corrugations and interlock therewith and thus firmly hold the tie against accidental displacement, although allowing it to be removed when necessary. When withdrawn from the tie, because there is no violent laceration of the wood, the fibers expand into the hole and close it sufficiently to enable the redriving of the spike without plugging the hole.

By reason of the triangular form of the spike, I materially reduce the weight of metal because I eliminate the metal that occupies two corners of the usual rectangular spike, and indicated in dotted lines in Fig. 2.

On the underside of the spike head I provide one or more ribs 15 that impinge or bite upon the top of the rail base, and restrain the creeping tendency of the rail.

I use the sharp point for the spike to ease the job of starting the spike.

I claim:—

A spike having a rail engaging head and a shank with an edge that is sinuous transversely, the remaining edges of the shank being straight lengthwise of the spike.

In testimony that I claim the foregoing I have hereinunto set my hand.

ISAAC L. EDWARDS.
